United States Patent [19]

Nakamura et al.

[11] Patent Number: Des. 303,957

[45] Date of Patent: ** Oct. 10, 1989

[54] OPTICAL DISK UNIT FOR ELECTRONIC COMPUTERS

[75] Inventors: Shingo Nakamura; Norio Shibuya, both of Tokyo, Japan

[73] Assignee: NEC Corporation, Tokyo, Japan

[**] Term: 14 Years

[21] Appl. No.: 943,295

[22] Filed: Dec. 18, 1986

[30] Foreign Application Priority Data

Jun. 19, 1986 [JP] Japan 61-23876

[57] CLAIM

The ornamental design for an optical disk unit for electronic computers, as shown and described.

DESCRIPTION

FIG. 1 is a front, top and left side perspective view of an optical disk unit for electronic computers showing our new design;

FIG. 2 is a front elevational view thereof on an enlarged scale;

FIG. 3 is a rear elevational view thereof on an enlarged scale;

FIG. 4 is a right side elevational view thereof on an enlarged scale, the left side being a mirror image;

FIG. 5 is a top plan view thereof on an enlarged scale;

FIG. 6 is a bottom plan view thereof on an enlarged scale.

FIG.1

FIG.2

FIG.3

FIG.4

FIG.5

FIG.6
